DOUBLE TWIST TWISTING SPINDLE

Otto Bochmann, Remscheid-Lennep, Germany,
assignor to Barmer Maschinenfabrik, Aktien-
gesellschaft, Wuppertal-Oberbarmen, Germany

Application May 20, 1939, Serial No. 274,790
In Germany May 24, 1938

1 Claim. (Cl. 57—58)

This invention relates to a double twist twisting spindle, in which the thread guide and the bobbin holder connected therewith are held stationary, that is do not participate in the rotation 5 of the spindle. The stationary bobbin holder serves for receiving the creel bobbin, whereas the stationary thread guide serves on the one hand for guiding the thread balloon and on the other hand for taking up the weight for keeping 10 the two parts stationary. The thread guide, which is mostly of bell shape, is closed at its upper end, that is towards the creel bobbin, so that this bobbin can only be set on the bobbin holder projecting beyond the thread guide. Alone this 15 construction of the spindle results in a very great constructional height. According to the working process for which such a double twist twisting spindle is to be used, it is desirable to accommodate 20 within the thread balloon a creel bobbin with the greatest possible quantity of thread. Seeing that, however, as mentioned above, the creel bobbin rests on the thread guide in the known double twist twisting spindles, the size 25 of the creel bobbin soon reaches its maximum limit.

Every increase in the size of the bobbin is accompanied by a corresponding enlargement of the thread balloon, with the result that the air resistance to the thread balloon increases correspondingly. If this resistance exceeds a certain limit, thread breakages frequently occur which prevent further perfect twisting. It may also happen that, if the constructional height of the spindles exceeds a certain limit, the thread balloon 30 will not become free at all but will swing inwards, so that twisting is no longer possible. In order to counteract these objections, it is evident that in these instances the speed of rotation 35 of spindle can be reduced, but this on the other hand would jeopardize the economical operation.

The object of the present invention is to design a double twist twisting spindle of the above mentioned type so as to enable the accommodation 40 of the largest possible quantities of thread within the thread balloon without causing detrimental effects. The invention proper consists in that the stationary thread guide for accommodating the creel bobbin is constructed as an open bell and the creel bobbin rests on the bottom of the bell. At the same time it is advisable, to arrange on the bottom of the bell a base-like projection on which the creel bobbin 45 is set and centred. If the thread guide is held still by a weight, this may be accommodated with- 50 in the sleeve-shaped creel bobbin.

By this construction it is possible to accommodate even large quantities of thread, that is correspondingly large creel bobbins within the thread balloon, without influencing the constructional height of the spindle and the size of the thread 5 balloon. Consequently, it is possible to perfectly work large quantities of thread without running the danger of thread breakage or of collapse of the thread balloon. Another advantage 10 is, that in working up larger quantities of thread all reduction in the speed of rotation of the spindle is avoided so that the full capacity of a double twist twisting spindle according to the invention is maintained. Consequently the present invention ensures the possibility of advantageously and perfectly working up large quantities 15 of thread.

An embodiment of the invention is illustrated by way of example in longitudinal section in the only figure of the accompanying drawing. 20

A thread accumulating ring 2 is arranged on and rotates with the rotary spindle 1, which ring guides into the balloon the thread 4 unwinding from the creel bobbin 3. The twisting spindle also carries the stationary thread guide 5 and the 25 bobbin holder 6 which is also stationary. The thread guide 5 is constructed as a bell with its open side upwardly directed and has on its bottom an upwardly projecting base 7 for receiving the creel bobbin. The creel bobbin 3 30 in the form of construction rests on the bottom of the open bell 5. The thread guide 5 and the creel bobbin 3 are kept stationary preferably by a weight 8 which, in this instance, is accommodated in the interior of the creel bobbin and 35 consequently does not require any additional space. By this measure it is possible, to considerably increase the size of the creel bobbin and consequently the quantity of thread within the balloon, without influencing the height of the 40 spindle and consequently the size of the thread balloon.

I claim:

A double twist twisting spindle comprising in combination a rotary spindle, an accumulating 45 ring mounted on and rotatable with said spindle, a thread guide loosely mounted on said spindle and of bell shape with its open side directed upwards, a base projecting from the inner side of the bottom of said bell-shaped thread guide, a sleeve-like creel bobbin accommodated in said bell-shaped thread guide and fitted on said base, and a weight accommodated in said bobbin for maintaining stationary said thread guide and said creel bobbin. 50

OTTO BOCHMANN.
